(73) Assignee: **Duright, LLC**, Eureka Springs, AR (US)

(57) **CLAIM**

(**) Term: **14 Years**

The ornamental design of a retractable leash with an integrated flashlight, as shown and described.

(21) Appl. No.: **29/323,160**

DESCRIPTION

(22) Filed: **Aug. 20, 2008**

FIG. 1 is a perspective view of the retractable leash with an integrated flashlight.

(51) **LOC (9) Cl.** **26-02**

FIG. 2 is a side view of the retractable leash with an integrated flashlight.

(52) **U.S. Cl.** **D26/38; D30/153**

FIG. 3 is a rear view of the retractable leash with an integrated flashlight.

(58) **Field of Classification Search** **D26/37, D26/38, 51, 41, 49, 46, 50; D30/151, 152; 362/157, 158, 253, 194, 197, 198, 190, 191, 362/200, 208; 119/796, 792, 789**

FIG. 4 is a front view of the retractable leash with an integrated flashlight.

See application file for complete search history.

FIG. 5 is a top view of the retractable leash with an integrated flashlight; and,

(56) **References Cited**

FIG. 6 is a bottom view of the retractable leash with an integrated flashlight.
